CLAIM

The ornamental design for a stand for electronic device, as shown and described.

DESCRIPTION

FIG. 1 is a front, top, right side perspective view of a stand for electronic device showing our new design;

FIG. 2 is a rear, top, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded rear, top, left side perspective view thereof.

The broken lines in the drawings show portions of the stand for electronic device that form no part of the claimed design.
